CLAIM

We claim the ornamental design for a data capture device, as shown and described.

DESCRIPTION

FIG. 1 is a front perspective view of an example data capture device;

FIG. 2 is a rear perspective view thereof;

FIG. 3 is a first side view thereof;

FIG. 4 is a second side view thereof;

FIG. 5 is top view thereof;

FIG. 6 is bottom view thereof;

FIG. 7 is a rear view thereof; and,

FIG. 8 is a front view thereof.

Broken lines of a particular embodiment are for purposes of illustrating environment and form no part of the claimed design.
